UNITED STATES PATENT OFFICE

96,141

DESIGN FOR A CASSEROLE

Maurice A. Smith, Jeannette, Pa.

Application March 12, 1935, Serial No. 55,850

Term of patent 14 years

To all whom it may concern:

Be it known that I, Maurice A. Smith, a citizen of the United States and a resident of Jeannette, in the county of Westmoreland and State of Pennsylvania, whose post-office address is care of McKee Glass Company, Jeannette, Pa., have invented a new, original, and ornamental Design for a Casserole, of which the following is a specification, reference being had to the accompanying drawing, forming a part hereof in which:

Figure 1 is a plan view and Figure 2 a side elevational view of the casserole, showing my new design.

I claim:

The ornamental design for a casserole as shown.

MAURICE A. SMITH.
